UNITED STATES PATENT OFFICE.

CARL LATHER, OF CHICAGO, ILLINOIS, ASSIGNOR OF ONE-HALF TO FRANK JOSEPH, OF CHICAGO, ILLINOIS.

VELOCIPED.

Application filed October 18, 1921. Serial No. 508,492.

To all whom it may concern:

Be it known that I, CARL LATHER, a citizen of the United States, and a resident of the city of Chicago, county of Cook, and 5 State of Illinois, have invented certain new and useful Improvements in Velocipedes, of which the following is a specification.

My invention relates to new and useful improvements in velocipedes and has for its 10 principal object the provision of an improved construction of this character which will be highly efficient in use.

A further object of my improved construction is the provision of a velocipede 15 constructed so as to accommodate one or more passengers by means of a simple adjustment embodied in the invention and which adjustment can be readily made by the average child. The structure of the adjustment is of such a simple construction 20 that the cost of manufacture will not be greatly increased over the cost of manufacturing a velocipede to accommodate a single passenger.

25 Other objects will appear hereinafter.

The invention consists in the combinations and arrangements of parts hereinafter described and claimed.

The invention will be best understood by 30 reference to the accompanying drawings forming a part of this specification, and in which,

Fig. 1 is a side elevational view of the invention.

25 Fig. 2 is a top plan view of the same.

Fig. 3 is a sectional detail view of the adjustable shaft embodied in the invention and taken substantially on line 3—3 of Fig. 1,

40 Fig. 4 is a fragmentary bottom plan view of the front end of the invention,

Fig. 5 is a vertical cross sectional view of the invention taken substantially on line 5—5 of Fig. 1,

45 Fig. 6 is a vertical cross sectional view of the same taken substantially on line 6—6 of Fig. 1, and

Fig. 7 is a sectional view taken substantially on line 7—7 of Fig. 6.

The preferred form of construction, as 50 illustrated in the drawings, comprises a main body member 10 having a hood 11 rigidly fixed adjacent the front end thereof, the shape of said hood being formed to represent an automobile motor hood. The body member 10 and the hood 11 are formed from

wood of any character which will serve the purpose. Slidably mounted on the opposite sides of the main body member are side body members 12 and 13, the front ends of which are arranged to snugly fit into a recess 14 60 provided in the hood 11, said side body members being held in spaced relation with respect to each other by space blocks 14' secured to the adjacent sides of said members. When the side body members 12 and 13 are 65 adjusted in their extreme rearward position, the front end portion 15 is supported in the recess 14 by the bottom portion 16 of the hood 11 as clearly shown in Fig. 1 of the drawings. The adjustability of the body 70 members 12 and 13 is governed by a transversely extending nut receiving bolt 17 permanently fixed on the main body member 10 adjacent the rear end thereof, and which engages longitudinally extending slots 18 75 formed in each of the side body members 12 and 13. Rigidly secured to the bottom member 16 of the hood 11, adjacent the front end thereof, by any suitable means, is a bearing member 19 having a longitudinally extending 80 recess 20 formed in its outer face. The bearing member 19 is preferably formed of wood and provided with a rearwardly extended portion 21 integrally formed therewith and which serves to check the strain of 85 the bearing member when the velocipede is in motion, as will be readily understood. Mounted in the recess 20 and secured to the bearing member 19 by means of a bolt 20', is 90 an axle 22 extending transversely with respect to the body members of the velocipede, said axle being mounted on wheels 23 and 24 which are swingingly mounted adjacent the outer ends thereof by means of stud axles 25. The wheels 23 and 24 are held in operative 95 position on the stud axles 25 by means of a suitable lock nut 25' threaded on the outer ends of each of the stud axles 25. The rear end of the velocipede is supported by a transversely extending axle 26 by means of curved 100 supporting members 27 and 28 rigidly fixed to the adjustable side body members 12 and 13 by means of nut receiving bolts 29, said supports having bearings 30 formed integral 105 therewith adjacent the lower ends thereof and through which the axle 26 is journaled. Mounted on the axle 26 are wheels 31 and 32 of the same character as the wheels 23 and 24, said wheels also being held in operative 110 position on the axle 26 by means of suitable

lock nuts 33. As shown in Fig. 1, I have provided mud guards or fenders 34 and 35 positioned adjacent the tops of each of the wheels, said fenders being formed of sheet metal or the like. The rear fenders 34 are supported in position by U-shaped supports 36 fixedly secured to the supporting members 27 and 28 and the front fenders 35 are supported in position by brackets 37 which are fixedly secured to the hood 11. The seating arrangement embodied in the invention comprises a main seat member 38 which is adjustably mounted on the main body member 10. The adjustable means 15 comprises a stud shaft 39 rigidly fixed to the bottom of the seat member 38 and slidably mounted in a vertical extending bore 40 formed through the body member 10 as shown in Fig. 6 of the drawings. A number 20 of equally spaced bores 41' are formed in the stud shaft 39 for the reception of an adjustable pin 41 which engages a recess 42, formed in the body member 10, when supporting the seat member in the desired position. To prevent the pin 41 from cutting or digging into the main body member 10, I preferably provide a metallic washer 43 interposed between the pin 41 and the main body member 10. By adjusting the pin 42 25 in the various bores 41', the seat member can be lowered or raised to accommodate the size of a child. The rear seating arrangement comprises a seat member 44 hingedly connected to a supporting member 45 which is 30 pivotally mounted on the side body members 12 and 13 by means of a bolt 46. The forward edge of the seat member 44 when in operative position rests upon the side body members as at 47 (Fig. 1), and is prevented 35 from collapsing by means of a transversely positioned supporting block 48 fixedly secured to the seat support 45 and engaging the edges of the side body members 12 and 13 as at 49 (Fig. 1). This arrangement is 40 such that when only one passenger occupies the velocipede the seat support is swung in a forward direction, as shown by dotted lines in Fig. 1, and the seat member 44 engages a recess 50 provided in the front seat member 38. After this operation has been accomplished the side members 12 and 13 are then moved into their extreme forward position, thus converting the velocipede into a single 45 passenger velocipede. A slot 51 is formed 50 in the front edge of the seat member 44 and extends rearwardly well into the body thereof, in alignment with the stud shaft 39 so as to allow the stud shaft to pass into the slot when the seat member engages the recess in 55 its extreme forward position. When the side body members 12 and 13 are in their extreme forward position the nut carried by bolt 17 is tightened so as to prevent the side body members from moving backwards when the 60 velocipede is in motion. A foot rest 52 is 65

secured to the side body members by means of wood screws or the like, and so positioned that the occupant of the rear seat can conveniently rest his or her feet thereon.

The steering mechanism as illustrated in 70 the drawings comprises oppositely disposed segment hand wheels 53 fixedly mounted on the upper end of a steering rod 54 which extends downwardly through a bore formed in the main body member 10. The steering 75 rod 54 is held in the proper position by means of a collar 55 which rests upon a wooden bearing 56 secured to the main body member 10 as shown in Fig. 1. The lower end of the steering rod 54 is pivotally connected to a connecting link 57 by means of a pin 58, said connecting link being slidably mounted through a lug 59 fixedly secured to the central portion of a V-shaped steering 80 rod 60. The outer ends of the V-shaped 85 steering rod 60 are connected to the stud axles 25 by means of an arm 61 integrally formed on each of the stud shafts 25' extending substantially at right angles with respect thereto, as best shown in Figs. 2 and 90 4 of the drawings. As will be readily understood, by turning the steering wheel in the desired direction, the wheels 23 and 24, through the medium of the steering rods, will be caused to turn in the direction in 95 which the steering wheel is turned.

The means for applying motive power to the wheels 31 comprises a transversely arranged shaft 62 journaled through bearings 63 integrally formed on the lower ends of a 100 U-shaped bracket 64 which is fixedly secured to the main body member 10 by means of wooden screws 65 or the like as shown in Figs. 1 and 6 of the drawings. Mounted on each end of the shaft 62 are foot pedals 66 105 and 67 of the usual construction. Fixedly mounted on the shaft 62 between the limbs 68 of the U-shaped bracket 64 is a face gear 69 which meshes with a pinion 70 fixedly mounted on the inner end of a hollow shaft 110 section 71 which extends longitudinally with respect to the body members. The inner end of the shaft 71 is supported by a bracket 72 which is fixedly secured to the U-shaped 115 bracket 64. Slidably mounted in the hollow shaft section 71 is a second shaft section 73 which together with the hollow shaft 71 constitutes a main shaft. The shaft section 73 is provided with a flattened portion 74 extending the entire length thereof and which 120 serves as a seat for the adjustable bolts 75 which rigidly hold the two shaft sections together when in the desired adjusted position. The rear end of the shaft section 73 is supported by a bracket 76 which is fixedly secured to the supporting member 27. Fixedly mounted on the extreme rear end of the shaft section 73 is a bevelled gear 77 which meshes with a co-operating bevelled gear 78 125 fixedly mounted on the rear axle 26. By this 130

arrangement motive power is transmitted to the rear axle by manually operating the foot pedals 66 and 67. By dividing the main shaft into two shaft sections, as disclosed in the drawings, the adjustable side body members 12 and 13 when moved to their extreme forward or rearward position the rear wheels 31 and 32 will naturally move in unison therewith, as well as the shaft section 73 which is slidably mounted in the hollow shaft section 71. When the shaft sections are properly in the adjusted position, the bolts 75 are tightened, thus serving to rigidly connect the shafts together.

From the foregoing description, one will be able to readily understand the operation of my improved velocipede and by carefully following the description, one is enabled to convert the velocipede into a single-seated or double-seated velocipede.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A vehicle of the class described comprising adjustable axle bearing body sections; wheels on said axle; means for transmitting motive power to said wheels; means for governing the direction of travel of said wheels; seat members mounted on said body, one of said seat members being pivotally mounted on one of said body sections; and a recess formed in the other of said seat members for the reception of the pivotally mounted seat member, substantially as described.

2. A vehicle of the class described comprising an axle bearing body section; an adjustable axle bearing body section embracing said first-mentioned body section; wheels on said axles; a manually operated drive shaft on said body sections; a bevelled gear on one end of said shaft; a co-operating bevelled gear on one of said axles meshing with said first-mentioned gear; seat members on said body sections, one of said seat members being pivotally mounted on one of said body sections; a recess formed in the other of said seat members for the reception of the pivotally mounted seat member; and means for governing the direction of travel of said vehicle, substantially as described.

3. A velocipede comprising an axle bearing body section; a second axle bearing body section embracing the opposite sides of said first-mentioned body section, said second

body section adapted to be adjusted longitudinally with respect to said first-mentioned body section; wheels on the axles carried by said body sections; a vertically adjustable seat member on said first-mentioned body section; a seat support pivotally mounted on said second body section; a seat member hingedly mounted on said support; and a recess formed in said first-mentioned seat member for the reception of said pivotally mounted seat member, substantially as described.

4. A velocipede comprising an axle bearing body section; a second axle bearing body section embracing said first-mentioned body section and adjustable longitudinally with respect thereto; means for fixedly securing said body sections in the desired adjusted position; seat members on said body sections; wheels on the axles carried by said body sections; a depending U-shaped support mounted on said first-mentioned body section; a manually operated shaft journalled on said support; a face gear on said shaft; an adjustable drive shaft supported by said U-shaped support and said second-mentioned body section and operatively connected to one of said axles; and a pinion on said drive shaft meshing with said face gear, substantially as described.

5. A velocipede comprising an axle bearing body section; a second axle bearing body section surrounding said first-mentioned body section; a vertically adjustable seat member on said first-mentioned body section; a seat member support pivotally mounted on said second-mentioned body section; a seat member hingedly connected to said support; a recess formed in said first-mentioned seat member for the reception of said hingedly mounted seat member; wheels on the axles carried by said body sections; a depending U-shaped support mounted on said first-mentioned body section; a manually operated shaft journalled on said support; a face gear on said shaft; an adjustable drive shaft supported by said U-shaped support and said second-mentioned body section and operatively connected to one of said axles; and a pinion on said drive shaft meshing with said face gear, substantially as described.

6. A velocipede comprising a wheeled body; seat members on said body, one of said seat members being pivotally mounted on said body; a depending U-shaped support mounted on said body; a manually operated shaft journalled on said support; an adjustable driving shaft supported by said U-shaped support and said body; operative connections between said manually operated shaft and said driving shaft; and operative connections between said driving shaft and said wheels, substantially as described.

7. A velocipede comprising wheeled body

sections; seat members on said body sections; means for governing the direction of travel of said body sections; a depending U-shaped support mounted on one of said sections; a manually operated transversely extending shaft journaled on said U-shaped support; a face gear mounted on said shaft; a hollow shaft section supported by said U-shaped support; a pinion on said hollow shaft section meshing with said face gear; a shaft section slidably mounted in said hollow shaft section and supported by one of said body sections; operative connections between said slidably mounted shaft section and said wheels; and means for rigidly securing said shaft sections in the desired adjustable position, substantially as described.

8. A velocipede including a wheeled body, a seat member pivotally mounted on said body, a seat member on said body adjacent said first named seat member and having a recess formed therein for the reception of said first named seat member when not in use.

25 9. A velocipede including wheeled body members mounted for longitudinal adjustment, a seat member pivotally mounted on said body, a seat member on said body adjacent said first named seat member and having a recess formed therein for the reception of said first named seat member when not in use.

30 10. A velocipede including a body comprising parts mounted for longitudinal adjustment, a pivotally mounted seat member on one of said parts, an adjustable seat member on the other of said parts having a recess formed therein for the reception of the other 40 of said seat members, wheels on said parts, and means for transmitting motive power to said wheels comprising foot operated means and a drive shaft in operative connection with said wheels and comprising parts 45 mounted for longitudinal adjustment.

11. A velocipede comprising a body member; a hood having recesses formed therein at one end of said body member; body members disposed on opposite sides of said first 50 named body member and having registering slots formed therein and having end portions engaging the recesses of said hood;

a member carried by said first named body member and extending through said slots to permit longitudinal adjustment of said body members; wheels carried by said body members; and adjustable driving means operatively connected to said wheels.

12. A velocipede comprising a body member; a hood having recesses formed therein at one end of said body member; body members disposed on opposite sides of said first named body member and having registering slots formed therein and having end portions engaging the recesses of said hood; a member carried by said first named body member and extending through said slots to permit longitudinal adjustment of said body members; wheels carried by said body members; adjustable driving means operatively connected to said wheels; and seat members adjustably carried by said body members.

13. A velocipede comprising a wheel bearing body member; wheel bearing body members disposed on opposite sides of said first named body member and provided with registering slots, said body members being adapted to be adjusted longitudinally with respect to each other; a member carried by said first named body member and passing through said slots for securing said body members in the desired adjustable position.

14. A velocipede comprising a wheel bearing body member; wheel bearing body members disposed on opposite sides of said first named body member and provided with registering slots, said body members being adapted to be adjusted longitudinally with respect to each other; a member carried by said first named body member and passing through said slots for securing said body members in the desired adjustable position; and seat members adjustably carried by said body members.

In testimony whereof I have signed my name to this specification in the presence of two subscribing witnesses.

CARL LATHER.
